ROTARY DRILL BIT

Joseph J. Whalen, Oklahoma City, Okla.

Application January 2, 1940, Serial No. 312,049

4 Claims. (Cl. 255—61)

This invention relates to earth boring drill bits, and is adapted for use in connection with the type of well drilling equipment generally known as rotary well drilling apparatus. It is an improvement over the invention covered by my Patent Number 2,119,661 issued June 7, 1938.

It is the chief object of the invention to provide a tool of this class which will greatly reduce the frequency of drilling shut downs for the purpose of replacing worn drill bit cutting teeth.

Other objects of the invention are similar to those outlined in the above mentioned patent, namely: to provide a bit which is adapted to carry a large number of cutting teeth, only a comparatively small number of which contact the well bottom at the same time, and which teeth, during the drilling operation, are automatically and progressively moved into earth contacting position when preceding teeth have performed their cutting function and have thereby become dull and worn; and to provide a bit which may be supplied with new cutter teeth and replaced in the well without the necessity of first reaming the hole.

The details in the construction of a preferred form of my invention, together with other objects attending its production, will be better understood from the following description when read in connection with the accompanying drawings which are chosen for illustrative purposes only, and in which

Figure 1 is a broken longitudinal sectional view of a bit embodying the invention, and is taken along the line 1—1 of Figure 5;

Figure 2 is a fragmentary longitudinal sectional view taken along the lines 2—2 of Figures 1 and 5;

Figure 3 is a perspective view of a preferred form of a cutter tooth carrying section, segment, or link, a plurality of which are connected together to form an elongated cutter tooth chain;

Figure 4 is a longitudinal sectional view taken through three of said sections or segments, and shows the details in the construction of each individual section, as well as the details of construction of the assembled chain;

Figures 5 and 6 are transverse sectional views taken respectively along the lines 5—5 and 6—6 of Figure 1;

Figure 7 is a perspective view of the lower end only of this preferred form of bit;

Figure 8 is a transverse sectional view taken along the line 8—8 of Figure 1;

Figure 9 is a perspective view of a pin which

is a part of the bit, and shows the peculiar form of the pin.

Figure 10 is a perspective view of the bit which is illustrated in detail in the various other figures of the drawings; and

Figure 11 is a transverse sectional view taken along the line 11—11 of Figure 1.

Referring to the drawings the numeral 20 designates an elongated bit body, the upper end 10 of which is threaded in the usual manner for connection to the lower end of a drill stem. The lower end of the bit is cross-sectionally shaped as shown in Figures 1 and 8 to carry a pair of wheels 21 and 22, which are respectively mounted, preferably by means of roller bearings 23, on axles 24 and 25.

Each of these wheels is provided with a peripheral groove of a suitable cross-sectional shape, and each of these grooves is adapted to 20 complementally receive and hold a portion of a semi-flexible chain of cutter teeth, the two chains being designated by the numerals 26 and 27. With the chains in the positions shown in their respective wheel grooves (Figs. 1, 2, 8 and 25 10) the wheels 21 and 22, in co-operation with an adjacent portion of the bit stock 28, serve firmly to hold a portion of each chain in an earth 30 contacting position, as the bit stock is rotated about its longitudinal axis, much the same as a tool holder on a lathe holds a tool in work contacting position. In other words the arcuate portion of the lower end of the bit stock forms a continuation of one wall of each peripheral wheel groove above mentioned, and makes the 35 neck of each composite groove narrower than its base or bottom portion, as will be clearly seen at the bottom of Fig. 1, thus holding the complementally shaped chain sections securely in the groove of each wheel.

40 The semi-flexible chains 26 and 27 are made up of a plurality of identical sections, segments, or links 28 (Figs. 3 and 4) which in turn are made up of a plurality of thin plates 29, which lie flat against each other, and which are preferably secured together along one common edge only by means of a layer 30 of weld metal. A second layer 31 of extremely hard metal is then welded to the layer 30, and teeth 32 are formed. The various sections 28 are then connected together at some point or points along one edge, only, as illustrated clearly in Fig. 4, by means of a suitable comparatively soft and malleable metal indicated by numeral 33.

50 The chains 26 and 27 may be of any length depending on the length of the bit stock 20. The

major portion of each chain is housed in the bit stock in identical magazines 34 and 35. These magazines are in the form of elongated hollow tubes, the bores of which are of a cross sectional shape to loosely receive the connected chain sections, as shown clearly in Figures 6 and 11. These magazines are pressed into oppositely positioned longitudinally extending off center bore holes 49 and 50 in the bit stock, which bore holes are positioned so that the chains may pass from their respective magazines into their respective grooves in the wheels 21 and 22 with only a slight bend in the chains, as shown in Figure 1.

As a means of limiting the amount of chain which can enter the wheel grooves at any one time, I provide identical pins 36 and 37, the form of which is clearly shown in Figure 9. The relative positioning of these pins may be clearly seen from an examination of Figs. 2 and 8. The shank of each pin fits into a suitably sized hole in the bit stock 20, and is preferably held in position by spot welding. In Figure 8 it will be seen that the enlarged head of each pin projects a slight distance into the respective wheel grooves, thereby serving as stops to the further penetration of the wheel grooves by the respective chain ends.

As a means of continuously urging the chain ends against these pins during the drilling operation, I provide a pair of plungers or pistons 38 and 39 (Fig. 5), the preferred construction of which is clearly shown in Figure 1. These pistons respectively travel the space in the previously mentioned off center bore holes 49 and 50 between the upper ends of the magazines 34 and 35 and a transversely extending chamber 40, near the upper end of the bit stock. Each piston is provided with a suitable sealing ring 41, a rod or tube 42 sufficiently small in diameter to enter the bores of the respective chain magazines, and a stop or head pin 43 which is screwed into the body of the piston after the piston has been placed in its cylinder, and which contacts the upper wall of the chamber 40 and thus prevents the pistons from moving out of their respective cylinders. The chamber 40, as will be seen in Figures 1 and 5, communicates openly with both of the off-center bore holes 49 and 50 and with the fluid or mud circulation duct 44. Thus, fluid pressure applied through the drill stem to which this bit is attached, exerts a downward pressure on the tops of the two pistons 38 and 39, which in turn causes the piston rods 43 to exert a downward force on the upper ends of the respective chains 26 and 27. From Figures 1, 5 and 8 it will be seen that the lower end of the duct 44 communicates with a pair of spaced outlet ducts 45 and 46 which serve to discharge drilling fluid at the bottom of the hole adjacent each of the cutter teeth units. From Figures 1 and 5 it will be seen that the chamber 40 is preferably formed by milling the bit stock transversely, and then closing the open ends of the chamber with plates 47 and 48 properly welded in position.

By an examination of the chains 26 and 27, as illustrated in Figure 2, it will be seen that the teeth near those ends of the chains which rest against the stop pins 36 and 37 are ground away almost down to the layer 30 of softer metal. This is done so that when the softer metal layer 30 at the free end of each chain is worn thin as the drilling progresses, the individual plates 29 of which the chain sections 28 are composed, will one by one become separated from the main

body of the chain, and will thus be forced past the stops 36 or 37, due to the continuous pressure being exerted on the opposite ends of the chains by the respective pistons. Since the stop

5 pins 36 and 37 actually contact successive plates 29 along one of their edges only, the pressure being exerted by the pistons is actually tending to break the metal layer 30 which connects the various plates together, and to thus free the 10 plates 29 one at a time. As each plate breaks loose, the edge of that plate opposite the stop pin is forced to move up and out of its particular wheel groove, and as the teeth wear away and the plates 29 leave the wheel grooves one by 15 one, each of the chains gradually moves out of its magazine, and new cutting teeth (and chain sections) are continuously moved into the wheel grooves. The wheels 21 and 22 do not rotate about their axes except as new chain sections or 20 portions of chain sections enter their grooves. These wheels simply serve to hold a desirable number of cutter teeth in cutting position on the lower end of the bit as the bit is rotated at the bottom of the well, in the usual manner.

25 As a means of making sure that none of the individual plates sticks in its wheel groove and prevents the wheel from turning, I provide a pair of peculiar shaped guards 51 and 52, the head of which are of substantially the same cross sec-

30 tional size and shape as the wheel grooves, and which project into the respective wheel grooves, as in Figures 1 and 2. Each of the guard heads has a long sharp pointed nose 53 which arcuately follows the bottom of the wheel groove so as to

35 force a stuck plate out of the groove. The shanks of the guards are preferably welded in position in suitable recesses 54 and 55, formed in the bit stock, and this welding, of course, had to be done after the wheels are in position on the

40 spindles 24 and 25. In other words the guards 51 and 52 are placed in the grooves of the respective wheels 21 and 22, the wheels and guards are placed in position as units, and the guards are then welded in position. To those familiar

45 with the art it will be understood that as the individual plates 29 become detached one by one from the chain sections, they are picked up by the circulating drilling fluid and are thus carried out of the well, and present no interference to the drilling operation.

I call attention to the fact that each of the off-center bore holes 49 and 50 is provided with an open port, such as indicated by the numeral 56, and each of these ports is located at a dis-

55 tance slightly greater than the length of the piston (38 or 39) above the upper ends of the respective magazines 34 and 35. Each of these ports 56 is normally closed by a plug 57 of soft metal, rubber, or any suitable composition, which

60 plugs serve to prevent the entry of drilling fluid, sand, or detritus into the plunger cylinders 49 and 50, or the magazines 34 and 35 during the drilling operation. When the two plungers 38 and 39 reach the lower ends of their strokes the

65 plugs 57 are forced out of their respective ports 56 by the maintained fluid pressure in the drill stem, and drilling fluid flows out through these ports. This causes a drop in the fluid pressure

70 being maintained in the drill stem, and thus notifies the driller that all the chain has been used from the magazines. The bit may then be withdrawn from the hole and new chains put in the magazines. The replacement is accomplished either by removing the pins 36 and 37 and threading the chain into the respective wheel

grooves and then into the respective magazines as the wheels are slowly rotated, or by removing the wheels from their spindles, loading the magazines from their lower ends, replacing the wheels, and then starting the lower ends of the chains into the respective wheel grooves.

From this description it is apparent that I have provided a bit which carries a large number of reserve cutting teeth which are automatically moved into earth contacting position to replace teeth which have already served their cutting function and have become worn beyond further use in doing so, and which automatically moves the new teeth into cutting position while the bit is in operation at the bottom of the 15 hole, thus eliminating frequent shut downs to replace worn cutter teeth on the bit; a bit which gives the same fast cutting action as what is commonly known as a drag bit, yet the teeth of which will last many times as long as ordinary 20 drag bit teeth because it is possible to replace worn teeth with sharp ones while the bit is in operation.

While I have described and illustrated a specific embodiment of my invention, I am aware 25 that numerous alterations and changes may be made in the construction without transcending the inventive principle conceived and disclosed hereinabove, and I do not wish to be limited except by the prior art and by the appended claims. 30

I claim:

1. A rotary drill bit comprising: an elongated bit body having one of its ends adapted for rigid attachment to a drill stem; a cutter tooth magazine within said bit body; cutter tooth holding means for holding a plurality of cutter teeth in an earth cutting position on the lower end of said body; a plurality of laminated sections of cutter teeth semi-flexibly connected together in the form of a chain or string, a part of which is housed in said magazine; means for moving consecutive cutter teeth from said magazine into said holding means; and means preventing the movement of cutter teeth from said magazine into said holding means except as consecutive ones of the teeth held thereby become so worn by their cutting operation as to render them substantially useless in performing any further cutting function.

2. A rotary drill bit comprising: an elongated bit body having one of its ends adapted for rigid attachment to a drill stem; a cutter tooth magazine within said bit body; cutter tooth holding means for holding a plurality of cutter teeth in

an earth cutting position on the lower end of said body; a plurality of laminated sections of cutter teeth semi-flexibly connected together in the form of a chain or string, a part of which is housed in said magazine; a fluid pressure operated piston for moving consecutive cutter teeth from said magazine into said holding means; and means preventing the movement of cutter teeth from said magazine into said holding means except as consecutive ones of the teeth held thereby become so worn by their cutting operation as to render them substantially useless in performing any further cutting function.

3. In a rotary drill bit, a bit body; a wheel rotatably mounted on the lower end of said body; a peripheral groove in said wheel for holding a portion of a chain of cutter teeth in an earth cutting position at the lower end of said bit body; a semi-flexible laminated chain or string of cutter teeth; a magazine within the bit body for holding that portion of said chain which is not held by the peripheral groove of said wheel; means for urging successive portions of said chain from said magazine into the peripheral groove in said wheel; and means for preventing the movement of successive portions of said chain from said magazine into said peripheral groove until certain teeth held in said peripheral groove successively become so worn from the cutting operation as to be substantially useless in performing any further cutting function.

4. In a rotary drill bit, a bit body; a wheel rotatably mounted on the lower end of said body; a peripheral groove in said wheel for rigidly holding a portion of a chain of cutter teeth in an earth cutting position at the lower end of said bit body; a semi-flexible laminated chain or string of cutter teeth; a magazine within the bit body for holding that portion of said chain which is not held by the peripheral groove of said wheel; fluid pressure operated means for exerting a continuous pressure against the teeth in said magazine to move successive ones thereof into the peripheral groove in said wheel; and means for preventing the movement of successive teeth into said peripheral groove until the teeth held thereby successively become so worn from the cutting operation as to be substantially useless in performing any further cutting function; said wheel, as the drill bit is rotated about its own longitudinal axis, adapted to turn about its axis only as teeth from the magazine enter its peripheral groove.

JOSEPH J. WHALEN.
